(57) **CLAIM**

The ornamental design for a display screen or portion thereof with graphical user interface, as shown and described.

DESCRIPTION

FIG. 1 is a front view of a display screen or portion thereof with graphical user interface showing my new design in accordance to a first embodiment;

FIG. 2 is a front view thereof in accordance to a second embodiment;

FIG. 3 is a front view thereof in accordance to a third embodiment; and,

FIG. 4 is a front view thereof in accordance to a fourth embodiment.

The outermost broken lines illustrate the display screen or portion thereof and form no part of the claimed design. The remaining broken lines in the figures depict portions of the graphical user interface which form no part of the claimed design.

1 Claim, 4 Drawing Sheets
